BOTTLE CASE

Richard W. Cooper, Hutchinson, Kans.

Application October 20, 1949, Serial No. 122,384

1 Claim. (Cl. 220—21)

1

This invention relates to novel and useful improvements in bottle cases.

An object of this invention is to support a number of bottles in such a manner that they are each resiliently mounted and spaced from each other in order to minimize breakage.

Another object of this invention is to very easily and conveniently insert and remove bottles from a holder or rack, which holder or rack consists entirely of an upper frame with a pair of handles on it together with a plurality of intersecting strips having means integrally formed therewith for holding the bottles in spaced relationship to each other.

Ancillary objects and features of novelty, will become apparent to those skilled in the art, in following the description of the illustrated form of the invention, wherein:

Figure 1 is a top view of the device;

Figure 2 is a longitudinal sectional view of the device shown in Figure 1; and

Figure 3 is an enlarged sectional detail of construction showing a fragmentary part of the device with a bottle inserted therein.

In carrying out the invention I have provided an extremely simplified structure. It is essential that devices of this nature be simple in order that they be commercially feasible and practicable.

There is an upper frame 10 consisting of a pair of longitudinal sides and a pair of transverse sides integrally connected together at the smoothly curved ends 12, 14, 16 and 18. Intermediate the curves 14 and 12 as well as the curves 16 and 18 there are handles 20 and 22 which are preferably appropriately shaped wire pieces with hinges 24 at the ends thereof connected with the transverse sides.

Extending across the longitudinal sides and also across the transverse sides is a means which is secured to said upper frame which forms a bottom, sides of the device and individual bottle holders of a resilient nature. This means consists of a number of spaced transversely extending strips 26 and a number of spaced longitudinally extending strips 28. All of the transverse strips are identical and all of the longitudinal strips are identical. There is very little difference between the transverse strips and the longitudinal strips.

Reviewing Figure 2 the longitudinal strip 28 is shown as being formed of one piece construction. An upturned end 30 is connected by means of hinge connection 32 to one of the transverse sides of the frame. This hinge connection consists merely of a bight formed integrally with

the side 30. At the opposite end of the strip there is another upturned side 34 having a hinge connection 36 identical with the hinge connection 32. The sides 30 and 34 are smoothly curved to provide the necessary resiliency of construction.

A resilient bottle holder generally indicated at 38 is provided in the strips. This resilient bottle holder consists of a pair of side walls 40 and 42 which are integrally joined together at the upper ends thereof and which are touching but spreadable at the lower ends thereof. These walls are adapted to be pressed and deformed as shown in Figure 3 upon insertion of a bottle

44 or other container. Intermediate the upturned end 30 and the wall 40 there is a depressed portion 46 which has a rivet or the like 48 passed therethrough. This rivet also passes through a part of the strip 26 thereby joining the strips at their intersections.

The transverse strips 26 are provided with hinge connections with the upper frame 10 and upturned end portion. It is the upturned end portions which form the side walls of the device, while it is the hinged connections which connect the upper frame with the webbing of the device.

In operation when a bottle or the like is inserted in the individual pockets or compartments formed by the spaced upwardly extending projections, the walls of each are compressed or deformed, which deformation is reflected throughout the entire device, particularly the region adjacent the individual pocket which is being used.

At the intersection of the strip wherein the rivet 48 passes through, a criss-cross seat is formed for the bottom of the bottle thereby firmly supporting it.

In forming the various joints, any conventional expedient may be resorted to, as welding, brazing, riveting and others.

Having described the invention, what is claimed as new is:

An article holding case comprising an upper frame, a first set of resilient straps attached at their ends to opposite sides of said frame, a second set of resilient straps attached to other opposite sides of said frame and crossing the first-mentioned set of straps to thereby define junctions, each strap having an upwardly rising projection formed therein at spaced intervals, each projection consisting of two smoothly curved side walls, each side wall being curved from its upper end to its lower end and joined at its adjacent wall of the pair, one wall of four

projections nearest to one of said junctions defining a resilient pocket to hold an article whereby the article may be inserted into said pocket due to the curvature of said walls of said pairs of walls, and means holding said straps together at said junctions, and the lower ends of the walls of said pair of walls contacting each other but spreadable from each other due to the resiliency of said straps.
